UNITED STATES PATENT OFFICE.

ANTON L. JOHNSON, OF GALVA, ILLINOIS.

MAIL-RECEIVING APPARATUS.

1,175,768.

Specification of Letters Patent. Patented Mar. 14, 1916.

Application filed May 22, 1914. Serial No. 840,322.

To all whom it may concern:

Be it known that I, ANTON L. JOHNSON, a citizen of the United States, residing at Galva, in the county of Henry and State of Illinois, have invented certain new and useful Improvements in Mail-Receiving Apparatus, of which the following is a specification.

My invention relates to improvements in mail receiving apparatus and for its object aims to provide a mail bag receiver which is simple in construction, positive in operation, and consists of a comparatively small number of parts.

A further object of the invention contemplates the provision of a mail bag receiving device which, after the mail bag has been delivered thereto, will prevent the accidental removal of the same from the receiving device.

The above and additional objects are accomplished by such means as are illustrated in their preferred embodiment in the accompanying drawings, described in the following specification and then more particularly pointed out in the claim which is appended hereto and forms a part of this application.

In describing my invention in detail reference will be had to the accompanying drawings wherein like characters denote like or corresponding parts throughout the several views, and in which:—

Figure 1 is a side elevation illustrating the application of the invention; Fig. 2 is an elevation of the receiving apparatus, the jaws thereof being set to receive the mail matter acted upon; and Fig. 3 is a sectional view of the jaws, closed, showing the mail bag held therein.

Referring now to the drawings by numerals, 1 designates a suitable support upon which the receiving apparatus comprising the present invention is arranged. Said apparatus in its preferred embodiment comprises a pair of relatively movable clamping jaws 2 and 3, the said jaws being pivoted at one end as indicated at 4 to an extension or tongue 5 formed upon the upper end of an operating plate spring 6, the latter being bent intermediate its ends as indicated at 7 and terminating at its opposite end in an enlargement 8 having an opening 9 formed therein. A second tongue 10 is formed upon the spring 6 in spaced relation to the tongue 5 above mentioned, the opposite terminals of the jaws 2 and 3 being pivoted as at 11

thereto. By arranging the enlargement 8 of the spring 6 in such relation to the lower terminals of the jaws 2 and 3 as to provide for the movement of the said enlargement 60 relatively thereto upon the release of one of the jaws, it is apparent that the tension of the said spring 6 will be sufficient to provide for a closing of the jaws, the said jaws being movable toward each other upon their 65 pivot points 4 and 11.

As a means whereby the shock attendant upon the delivery of the mail matter acted upon to the receiving apparatus may be absorbed, the spring 6 and the jaws 2 and 3 70 carried thereby are yieldably supported through the medium of a plurality of helical springs 12 arranged in radial relation relatively to the said spring 6, the springs 12 being attached at one end to the said 75 spring 6 at a point adjacent the point receiving the blow of the mail bag, and at their opposite ends to the frame 1.

An arm 13 projects laterally from the frame 1, said arm having fulcrumed thereto 80 as indicated at 14 a trip lever 15, said lever being enlarged at its free end as indicated at 16, the enlargement being disposed directly in the path of the mail matter acted upon to receive the impact occasioned by 85 the delivery of the said mail bag thereto. A trigger 17 pivoted as at 18 is mounted upon the frame 1, the free end of the trigger being adapted for arrangement beneath the opposite end of the lever from that upon 90 which the enlargement 16 is formed to provide for a holding of the jaws 2 and 3 open and against tension of spring 6.

Operation is as follows: The mail matter to be delivered to the receiving apparatus 95 being suspended in any suitable manner, preferably as illustrated in Fig. 1 at a point adjacent the door of the car, will, as the car moves in the direction indicated by the arrow in the said Fig. 1 cause the said mail bag to move into engagement with the enlargement 16 of the operating lever 15. The impact of the bag with the said enlargement will so actuate the lever as to provide for disengagement of the said lever with 100 the trigger 17. The moment trigger 17 is disengaged, jaws 2 and 3 are released, and the tension of spring 6 is sufficient to cause said jaws to automatically close and grasp the mail bag therebetween, any suitable material such as canvass 19 being provided 105 to hold the mail matter between the jaws 110.

until subsequently removed. The canvass covering forms a part of the respective jaws.

From the foregoing, taken in connection with the accompanying drawings it is apparent that by the provision of the several springs designated 12, the stress and strain incident to a transfer operation will be greatly relieved; that the actuation of the jaws upon engagement of the mail matter with the trip lever will be instantaneous and positive; and that by the novel arrangement of the spring 6 relatively to the said jaws, but a single spring is necessary to provide for the automatic movement of both jaws.

In reduction to practice, I have found that the form of my invention, illustrated in the drawings and referred to in the above description, as the preferred embodiment, is the most efficient and practical; yet realizing that the conditions concurrent with the adoption of my device will necessarily vary, I desire to emphasize the fact that various minor changes in details of construction, proportion and arrangement of parts may be resorted to, when required, without sacrificing any of the advantages of my invention, as defined in the appended claim.

Having thus fully described my invention,

Copies of this patent may be obtained for five cents each, by addressing the "Commissioner of Patents, Washington, D. C."

what I claim as new and desire to secure by Letters Patent, is:—

In a mail receiving apparatus, an upright supporting frame, a resilient arm projecting laterally of said frame, coacting clamping jaws movable on a vertical axis into and out of engaging relation, an actuating spring therefor, a plurality of radially arranged helical springs attached at one end to said actuating spring and at their opposite ends to said frame to yieldingly maintain said clamping jaws in a receiving position, a trip plate pivoted to said arms to move therewith, and a trigger fastened to said frame for engagement with said trip plate to maintain the said jaws open and against a closing tendency occasioned by said actuating spring, the mentioned helical springs and the mentioned resilient arm jointly receiving and absorbing the shock occasioned by the impact of mail matter with said receiving means, substantially as described.

In testimony whereof I affix my signature in presence of two witnesses.

ANTON L. JOHNSON.
